United States Patent Office

Des. 208,938
Patented Oct. 17, 1967

208,938

LUMINAIRE LENS

Vearl S. Wince, Newark, Ohio, assignor to Holophane
Company, Inc., New York, N.Y., a corporation of
Delaware

Filed Oct. 7, 1966, Ser. No. 4,191

Term of patent 14 years

(Cl. D48—16)

Fig. 7

Fig. 4.

FIG. 1 is a bottom perspective view of a luminaire lens showing the new design;

FIG. 2 is an end view of the luminaire lens shown in FIG. 1;

FIG. 3 is a section taken along the line 3—3 of FIG. 1;

FIG. 4 is a bottom view of the luminaire lens of FIG. 1 indicating that the prismatic pattern is repeated throughout the central portion of the lens;

FIG. 5 is a top view of the luminaire lens of FIG. 1, indicating that the prismatic pattern of the central portion of the lens is repeated throughout its length;

FIG. 6 is a side view of the luminaire lens of FIG. 1, with the central portion thereof indicated diagrammatically;

FIG. 7 shows a portion of FIG. 4 on a larger scale than FIG. 4;

FIGS. 8 and 9 are sections taken along the lines 8—8 and 9—9, respectively, of FIG. 7.

I claim:

The ornamental design for a luminaire lens, as shown and described.
